The ornamental design for a railway hose support bracket, as shown and described.

DESCRIPTION

FIG. 1 is a rear perspective view of a railway hose support bracket showing the new design;

FIG. 2 is a front elevational view thereof;

FIG. 3 is a back elevational view of the side opposite to that of FIG. 2;

FIG. 4 is a left side elevational view;

FIG. 5 is a right side elevational view of the side opposite to that of FIG. 4;

FIG. 6 is a top plan view thereof; and,

FIG. 7 is a bottom plan view thereof.

The broken lines immediately adjacent the solid line and shaded portions of the drawing figures represent the bounds of the claimed design, while all other broken lines depict portions of the railway hose support bracket that form no part of the claimed design.
